G. E. PHILP

BEDSPRING STRETCHER

Filed Nov. 5, 1923

Inventor
George E. Philp;

R. S. Berry
Attorney.

UNITED STATES PATENT OFFICE.

GEORGE E. PHILP, OF LOS ANGELES, CALIFORNIA.

BEDSPRING STRETCHER.

Application filed November 5, 1923. Serial No. 672,840.

To all whom it may concern:

Be it known that I, GEORGE E. PHILP, a citizen of the United States, residing at Los Angeles, in the county of Los Angeles and State of California, have invented new and useful Improvements in Bedspring Stretchers, of which the following is a specification.

This invention particularly pertains to a device for stretching bed springs of a woven wire type and which is specially applicable for use in taking up the slack or sag of worn bed springs in effecting repairs thereof.

15 An object of this invention is to provide a device which is attachable to a bed spring frame and engageable with the springs, and which is operable to stretch the springs and temporarily hold same in a stretched condition until the springs can be permanently secured.

Another object is to provide a simple means for readily effecting engagement between the stretcher and the bed frame and the springs.

A further object is to provide a device of the above character embodying a plurality of separate tensioning devices adapted to be positioned at various points transversely of a spring frame so as to exert a longitudinal pull on the springs at any desired point throughout the width thereof.

With the foregoing objects in view together with such other objects and advantages as may subsequently appear, my invention resides in the parts and in the construction, combination and arrangement of parts hereinafter described and claimed and illustrated by way of example in the accompanying drawings, in which—

Fig. 1 is a plan view of a bed spring showing the invention as applied.

Fig. 2 is a view in section as seen on the line 2—2 of Figure 1 illustrating the tensioning element, and showing the manner of attaching same to the bed springs and frame.

Fig. 3 is an end view of the tensioning element shown in Figure 2.

50 Fig. 4 is a detail in section as seen on the line 4—4 of Figure 1, illustrating a means whereby the stretcher may be temporarily clamped to the bed frame to hold the springs taut if it is desired to remove the stretching elements or to shift their position.

Fig. 5 is a detail in perspective illustrating a modified form of the adjustable mounting of the tensioning element.

More specifically, 6 indicates a bed spring which embodies a pair of side rails 7 and 8, an end rail 9, and a woven wire spring 10, stretched upon the bed frame and held in place by a retaining cleat 11 in the usual manner.

Fig. 5 is a detail in perspective illustrating a modified form of the adjustable mounting of the tensioning element.

60 In carrying out my invention I employ a spring-engaging clamp 12 comprising a pair of bars 13 and 14 adapted to extend transversely across the bed springs with the bars arranged on opposite sides thereof; the 70 clamp bars being connected together at suitable intervals throughout their lengths by a series of clamping devices 15. The clamping device 15 is here shown as embodying a bolt 16 which is adapted to be passed 75 through aligned openings 17 and 18 in the bars 13 and 14 when the latter are positioned in parallel relation astride the bed springs, as shown in Fig. 4; the bolt being preferably passed upwardly from underneath the lower bar 14 through the woven wire fabric of the spring and thence through the perforations 17 in the bar 13 with its threaded end projecting above the latter to receive a wing nut 19. The bars 13 and 14 are formed with the perforations 17 and 18 80 comparatively close together throughout their lengths so that adjacent bolts 16 may be engaged with the spring either close together or spaced at greater intervals apart, 85 whereby the point of engagement between the bars and the springs may be located at points throughout the width of the spring where it is desired to apply a greater tension.

90 A series of tensioning devices 20 are provided, each of which comprises a threaded shaft 21 mounted to rotate on a U-clamp 22 adapted to be engaged with the end rail 9 of the bed spring frame; the threaded shaft 105 being engageable with an internally threaded sleeve 23 carried by the spring-engaging clamp 12. The sleeve 23 is adapted to be disposed at any desired position longitudinally of the spring-engaging clamp, for which purpose it is provided with a threaded stem 24 projecting from one side thereof which stem is adapted to be inserted downwardly through a pair of the aligned openings 17 and 18 through the bars 13 and 14 110 and be engaged with a nut 25 by which the sleeve is held in place,

The U-clamp 22 embodies a U-frame the side members 26 and 27 of which are of different lengths. The U-frame is adapted to be set astride the end rail 9 of the bed frame from the under side thereof with the short side member 26 of the frame extending beneath the springs 10 and with the elongated frame member 27 projecting upwardly at the end of the spring frame, as particularly shown in Fig. 2.

The frame member 26 carries a clamping screw 28 which is threaded in the frame member 26 and is adapted to bear against the inner face of the frame member 9 to clamp the U-frame in position on the spring frame. The elongated side member 27 of the frame is formed with spaced superposed openings 29 and 30 through either of which the threaded stem 21 extends according to the height desired to space the shaft 21 from the lower portion of the U-frame, and whereby the device is adapted to be applied and operated with spring frames of various heights.

The shaft 21 is fitted with a crank 31 which is engaged with the end of the shaft 21 projecting through a frame member 27 whereby the shaft may be readily rotated.

It will now be seen that the tensioning members 20 may be disposed at any desired point throughout the width of the bed springs and that any desired number of the tensioning devices may be employed, as occasion may require. In some instances, it may only be necessary to employ but one of the tensioning devices, and in others it may be necessary to employ two or more, but in any event, by reason of the tensioning devices being engaged with the spring-engaging clamp at various points throughout the width of the spring, the tensioning devices may be disposed so as to exert a pull at points where it is desired to take up the slack in the bed spring.

A modified form of the mounting of the tensioning members on the spring clamp 12 is shown in Fig. 5, and embodies a sleeve 32 which is slidably mounted on the upper bar 13 and has upstanding lugs 33 formed with an internally threaded opening 34 in which the threaded shaft 21 is screwed; the sleeve 32 being adapted to be moved longitudinally of the bar 13 into any desired position.

Means are provided whereby the spring clamp 12 may be temporarily secured to the side members 7 and 8 of the spring frame, as where it is desired after placing the spring 10 under tension, to remove, replace or change the position of the tensioning devices 20.

This means is here shown in Fig. 4 as comprising a U-bolt 35 which is adapted to be placed astride the side frame 7 or 8 from

the under side thereof, and to have its end 65 portions inserted through the openings 17 and 18 of the bars 13 and 14 adjacent opposite sides of the rails 7 or 8 to receive wing nuts 36 and 37.

The portion of the U-bolt 35 extending 70 beneath the rail 7 or 8 is formed with teeth 38 adapted to engage the side rail so as to hold the U-bolt against sliding movement on the rail.

In the use of the device, the spring engaging clamp is secured to the spring 10 in the manner described and the tensioning shafts 21 are each rotated successively to draw the bars forward, thus stretching the spring. By turning one shaft 21 a greater 80 amount than the other shafts, portions of the spring may be stretched more than other portions. Also by omitting some of the bolts the same effect may be obtained.

When the spring has been stretched the 85 desired amount the spring clamps may be secured to the side rails of the spring frame to hold the spring in its stretched position, and the shafts 21 may be removed to facilitate re-securing the spring permanently in 90 its stretched condition upon the frame. To do this the cleat may be removed, and the loose end of the spring brought forward by the bars is cut away and the spring re-secured by the cleat. When the U-clamps and 95 bars are removed the spring is then in a fully stretched condition, all sagging portions having been drawn up.

Whereas, I have shown and described a 100 specific construction and arrangement of parts I do not wish to be confined thereto but may use such constructions and combinations of the salient features of the invention as come within the scope of the appended claims.

I claim—

1. In a bed spring stretcher, a pair of parallel bars, means for clamping said bars together with a bed spring interposed therebetween, a series of internally threaded members on one of said bars adapted to be adjusted to various positions longitudinally of the bar, threaded shafts engaging said members, and means for supporting said shafts against longitudinal movement on a spring frame.

2. In a bed spring stretcher, a pair of parallel bars, means for clamping said bars together with a bed spring interposed therebetween, a series of internally threaded members on one of said bars adapted to be adjusted to various positions longitudinally of the bar, threaded shafts engaging said members, means for supporting said shafts against longitudinal movement on a spring frame, and means for temporarily securing said bars to a portion of a spring frame.

GEORGE E. PHILP.
